Leontine

UNITED STATES PATENT OFFICE.

LE ROY R. OWEN AND OWEN E. WHITEMAN, OF SOUTH BEND, INDIANA.

SCREED CHAIR.

Application filed July 30, 1927. Serial No. 209,573.

This invention relates to a screed chair, the general object of the invention being to provide means whereby the chair can be easily and quickly put in place without interfering with the reinforcing material and with the use of but few tools.

Another object of the invention is to so form the device that parts thereof can be used over and over again.

10 This invention also consists in certain other features of construction and in the combination and arrangement of the several parts, to be hereinafter fully described, illustrated in the accompanying drawings and 15 specifically pointed out in the appended claims.

In describing our invention in detail, reference will be had to the accompanying drawings wherein like characters denote 20 like or corresponding parts throughout the several views, and in which:—

Figure 1 is a view partly in section, showing the device in use.

Figure 2 is a similar view but taken a 25 quarter turn from Figure 1.

As is well known, in building concrete floors, the concrete is leveled by a straight-edge resting on what is known as screeds, these screeds being metal pipes or pieces of 30 wood. The screeds are supported on chairs which must be attached to portions of the forms before the cement is poured on the forms and heretofore it has been a difficult 35 matter to place these chairs in position, as the reinforcing material for the concrete makes installation difficult.

In carrying out our invention, we provide 40 an L-shaped rod 1 which is threaded as shown at 2, so that it can receive a wing nut 3, the threaded portion being adapted to pass through a hole 4 made in a part of the form A. By making this rod of L-shape, the short limb thereof acts as a handle so that a wrench 45 is not needed to turn the rod. A channel member 5 has each limb thereof formed with a threaded hole, one of which receives the threaded end of the rod 1 and the other receives the threaded end of a rod 6 which has its upper end shaped to receive the screed 50 B. The drawing shows the upper end of

the rod 6 as bent to form a curved recess 7 to receive the pipe form of screed shown, but if a flat screed is to be used, the upper end of the rod 6 would be formed flat.

From the foregoing it will be seen that 55 with this form of chair, it is simply necessary to bore a hole, such as 4, in the form to receive the rod 1 and with a long bit, such a hole can be easily bored without interference on the part of the reinforcing material. 60 One man below the form would handle the rod 1 and the nut 3, while a second man above the form would hold the channel member 5 as the rod 2 is being screwed into the same. Thus the chair can be easily and quickly installed by two men. Of course, the parts 5 and 6 will remain in the concrete floor, but the parts 1 and 3 can be removed and used over and over again. The small hole left by the member 2 can be easily covered up 65 and pointed with concrete. By threading the rods 1 and 6 into the member 5, the parts can be adjusted to be used with different thicknesses of floors.

It is thought from the foregoing description that the advantages and novel features of our invention will be readily apparent.

We desire it to be understood that we may make changes in the construction and in the combination and arrangement of the several 80 parts, provided that such changes fall within the scope of the appended claims.

What we claim is:—

1. A device of the class described comprising an L-shaped rod having its long arm 85 threaded and adapted to be passed through a hole made in a form, a channel member having a threaded hole in each limb thereof, the hole in the lower limb receiving the end of the threaded rod, a nut on said rod for 90 engaging the lower face of the form while the channel member engages the upper face thereof, a second rod having its lower end threaded to engage the upper hole in the channel member and its upper end shaped to 95 form a seat for a screed.

2. Screed supporting means comprising a screw threaded member having a handle thereon, with its threaded portion adapted to be passed through a hole in a form, a cen- 100

tral member having upper and lower threaded holes therein, the lower hole receiving the threaded portion of said member when said central member rests upon the form, a nut 5 on the threaded part of the member for engaging the lower face of the form, with the central member engaging the upper face

thereof and a screed supporting member having its lower end threaded to engage the upper threaded hole in the central member. 10

In testimony whereof we affix our signatures.

LE ROY R. OWEN.
OWEN E. WHITEMAN.
